UNITED STATES PATENT OFFICE.

JOSEF WINTERMAYR, OF VIENNA, AUSTRIA-HUNGARY.

POWER-LOOM.

1,054,734.

Specification of Letters Patent.

Patented Mar. 4, 1913.

Application filed May 21, 1908. Serial No. 434,040.

To all whom it may concern:

Be it known that I, JOSEF WINTERMAYR, a citizen of Austria, residing at Vienna, in the Province of Lower Austria and Empire 5 of Austria-Hungary, have invented certain new and useful Improvements in Power-Looms, of which the following is a specification.

At present there are used for the mechanical production of fabrics two classes of power looms, one having positive movement of the lathes and others having freely falling lathes. Looms of the former class have the disadvantage that the warp threads are 15 excessively subjected to a strain while in the latter type of loom this disadvantage is removed, but instead of it the disadvantage is found that the falling lathe cannot be stopped at any point in its movement and especially not in its downward movement. 20 This results in numerous faults in weaving which, especially in the manufacture of wire cloth, for which this invention is mainly intended, are very objectionable.

My invention consists in the arrangement 25 of a brake mechanism on the lathe actuating shaft operated indirectly from the driving shaft which is made dependent on the actuating mechanism of the loom in such manner 30 that on the disengagement of said actuating mechanism, either automatically or by hand, through any cause whatever, the said brake mechanism is instantly and automatically brought into action stopping the lathe actuating shaft in its position at that moment.

It is of advantage to provide the driving 35 means with an electro-magnetic clutch and also to construct the brake acting on the lathe actuating shaft as an electro-magnetic clutch, since thus, by the arrangement of a simple switch, on the release of the driving clutch, the brake can be caused to operate.

In the accompanying drawings, showing 40 one embodiment of my invention, Figure 1 is an end elevation of a loom in which the lifting of the lathe is effected by levers and cams. Fig. 2 is a plan of the driving shafts. Figs. 3, 4 and 5 are enlarged detail views 45 of the switch mechanism for operating the clutches. Figs. 6 and 7 are enlarged detail views of the switch operating mechanism actuated by the feeler. Fig. 8 is an enlarged detail view of the mechanism preventing the lathe from swinging out too far. Fig. 9 is a diagram of the electric circuit for the same.

From the main shaft 1, which is driven through an electro-magnetic clutch 2, power is transmitted to the intermediate shaft 3 which transmits motion to the shaft 4 for driving the shedding mechanism of the loom and to the lathe actuating shaft 5.

According to Figs. 1 and 2, the shaft 5 carries an arm 6, whose free end comes into the path of a roller 7, which is carried by a disk 8 mounted on the continuously driven shaft 3 in such a manner that for every complete revolution of the shaft 3 the arm 6 is rocked with it once and the shaft 5 turned through a predetermined angle and then released. A second arm 9 mounted on the shaft 5 takes part in this rocking movement, said arm being connected by a link 10 with the lathe 11. The angle about which the shaft 5 is turned on rotation of the shaft 3 and the length of the arm 9 determine the stroke of the lathe. When the arm 6 is released by the roller 7, the lathe brought out of its vertical position by the previous movement swings back again into the starting position and beats up the last passed shot of the fabric. On shaft 5 is mounted the braking device 12, which may be either purely mechanical, e. g. a block brake, spring-brake or friction brake, or, as in the preferred form, an electro-magnetic brake. It consists of a fixed part carrying the illustrated electro-magnets through which is freely passed the shaft 5, and of a part movable on the shaft 5 and rotatable therewith, 50 which part carries the armatures. By exciting the electro-magnets, the armatures are attracted and the shaft is braked. The windings of the brake 12 are connected through a switch with the windings of the electro-magnetic clutch 2, and a source of current in such a way that by breaking the clutch circuit the brake circuit is closed, and vice versa. When the brake circuit is closed, the rotating part of the brake presses 55 on the fixed part and the shaft 5 is held against further rotation and, through the said connection of the shaft 5 with the lathe 11, the latter is held in its position, whether it was rising or falling.

Upon the disengagement of the clutch 2 on shaft 1, however, the part 12^a of the clutch 12, which part is formed as an electro-magnetic brake, will be automatically thrown into operation to stop shaft 5. The 60 disengagement of the clutch 2 on shaft 1 and the operation of the brake clutch 12

take place in the following cases:—1, when the machine is to be stopped by hand for any reason; 2, when the shuttle has not traversed the whole length of the shed; 3, 5 when the lathe for any reason whatever is drawn backward too far; 4, when a warp thread breaks.

For the purpose first mentioned the adjustably arranged stop motion bar 18 (Figs. 3, 4 and 5) under the breast beam is connected by a link 19 with an arm 20 on the shaft 21, on which is also mounted a segment 22. This segment has two projections 23, (one only being shown in the drawing) one of which at a time engages a weighted lever 24 provided with a curved slot 25 and loosely mounted on the shaft 21. The curved slot 25 is engaged by a pin 26, which is connected by a link 27 with a 10 switch bar 28. A switch 29 carried by the latter connects, according to its position, the middle contact *a* of the three contacts, *a*, *b*, *c*, which is connected with the source of current, with one or the other of the contacts 15 *b* or *c* of which the one (*b*) leads current to the driving clutch 2, the other (*c*) to the 20 brake clutch 12'.
25

According to the position of the parts shown in Fig. 3, the machine is in motion and the clutch 2 engaged. When the bar 18 is 30 moved toward the right in Fig. 3, the segment 22 first raises the weighted lever 24, which, as soon as it has overbalanced, falls toward the other side, and toward the end of 35 its movement carries with it the pin 26, the switch 29 being thereby suddenly shifted so that the circuit through *b* to the driving clutch 2 is opened and the circuit through *c* to the brake clutch 12' closed. On the return 40 movement of the stop motion bar 18 (toward the left in Figs. 3 and 5), for the purpose of throwing in the clutch 2, the tilting of the weighted lever 24 in the reverse direction and the movement of the switch 45 29 is suddenly effected, whereby sparking is avoided and positive shifting from one end position to the other is effected. The actuation of the two clutches 2 and 12 also takes place in the manner described, when 50 from any cause whatever the shuttle is locked in the shed.

On the lathe 11 is mounted a feeler 31 (Figs. 6 and 7) which, together with the pawl 32 is pivoted upon pin 33 and is 55 weighted at one side. In the loom frame and beneath the pawl 32 is movably mounted a rack 34, the upper side of which next the pawl is formed to correspond to the path described by the point of the pawl upon the 60 movement of the lathe. The rack is controlled by a spring 35 and carries a projecting pin 39. On the frame is pivoted upon a pin 36 a weighted lever 37, which carries a projection 38. The weighted lever is also 65 connected with the switch-bar 41 by a link

40, which bar 41 carries the contact piece 42 that controls the contacts *b'*, *a'* and *c'*. In normal condition the weighted lever is raised and the projection 38 lies behind the pin 39 of the rack 34. The contact piece 42 70 connects the contacts *a'*, *b'* for the driving circuit. When the shuttle ordinarily is held in the shuttle box, the pawl 32 passes freely over the teeth of the rack 34. If, however, the shuttle is not in the shuttle box, the 75 movement of the feeler 31 against the shuttle box causes the lowering of the pawl 32, which now engages in one of the teeth of the rack 34. In this case, owing to the movement of the falling lathe, the rack 34 is 80 moved while compressing the spring and the weighted lever 37 is thereby released from the pin 39. The weighted lever is now free to drop and thereby move the bar 41 so that the contact 42 interrupts the circuit of the 85 driving clutch 2 at *b'* and closes the circuit of the brake 12' at *c'*. The dimensions of the weighted lever 37 are such that the operation takes place, even if the rack 34 is 90 moved only very little under the pressure of the lathe. If the pawl 32 is released from the rack 34 and the weighted lever 37 again raised, the rack 34 is returned by its spring 35 to its normal position, in which it retains the weighted lever in its raised position. In 95 order to prevent this, a cushioning device (Fig. 8) is provided, which shifts the two clutches 2 and 12'. This consists of a buffer 43, mounted in the frame, one end of which lies in the path of oscillation of one of the 100 projections 44 on the lathe, while on the other side is mounted a depending lever 45 with an adjustable screw 46, the hook-shaped second arm 47 of which engages the pin 48 on a weighted lever 49 and thus 105 holds the latter in raised position. The weighted lever 49 is connected by links 50 with the switch-bar 52 carrying the switch 51. If the lathe swings too far back, its projection 44 presses back the buffer 43, 110 which moves the depending lever 45, 47 in such a manner as to release the pin 48 on the weighted lever 49. The latter drops and thereby shifts the switch 51 connecting the driving clutch 2 with the conductor 115 120 (through *b'*, *a'*) so that it now connects the contact *a'* connected by the source of current with the contact *c'* for the brake clutch 12. By raising the weighted lever 49 the switch is returned to its normal position. In order to, operate this arrangement upon the breakage of a warp thread, the usual warp thread controller is used, which consists of bars 53, insulated from the frame and presenting one pole, which, like the frame, is connected to a source of current, the circuit of which is closed by the breakage of a warp thread, which represents the second pole, on dropping on one of the bars 53.

The foregoing description assumed that 130

each switch was separately connected to the current conductor and to the two electro-magnetic clutches. It is advantageous, however, to supply the whole of the circuit-
 5 terminals with a current from a common source, which is obtained by the system of wiring shown in Fig. 9. In this figure S and R represent the two conducting wires, 2 is the driving clutch and 12 the brake
 10 clutch, while A, B, C and D represent the four switches in the order previously described.

As is clear, the clutch 2 is connected by a wire s with the conductor S and in succession (through the terminals b, a, b', a', b²,
 15 a², b³, a³, of the switches A, B, C, D) with the return wire R. The actuation of any one of the switches must as a consequence, cause the interruption of the circuit through
 20 the clutch 2. Electro-magnetic windings of the brake-clutch 12 are connected, on the one hand, by the wire z with the current supply S and on the other hand connected with the second wire t in parallel are the
 25 contacts c, c', c², c³ of the four switches A, B, C, D. As these contacts are not normally in the circuit, the clutch 12 remains inoperative, but is actuated whenever any one of the switches is shifted. In order to
 30 actuate the switch connected to the warp-thread controller, an auxiliary source of current (not shown) is used, which actuates a solenoid 54, the core of which acts through a link 55 and lever 56 on the bar 58 carrying
 35 the switch 57. It is evident, that in this manner simultaneously with the automatic or intentional stoppage of the loom the braking device is thrown automatically into operation to hold the lathe in the position,
 40 in which it is at that moment. In order to set the loom in motion again, only the hand switch is used. It is, therefore, a rule, after the automatic stoppage of the loom, first, to throw out the hand switch and then, after
 45 remedying the defect, to return the automatic switch which is operative for the time being, after which the loom is started by actuating the hand switch.

I claim:—

50 1. In a power loom with a freely falling lathe the combination with the lathe and the main driving-shaft, of an actuating shaft for the lathe operated indirectly from said driving-shaft, an electro-magnetic braking-device on said actuating-shaft, an electro-magnetic clutch on said driving-shaft, a common circuit for said braking-device and said clutch, a switch in said circuit adapted to throw in said clutch while throwing out
 55 said brake and vice versa, and means connected with said switch for effecting a rapid shifting thereof.

2. In power looms with a freely falling lathe, the combination with a lathe actuating shaft, of a driving mechanism including an electro-magnetic clutch, an electro-magnetic brake for said lathe actuating shaft, a source of current, a common circuit for said clutch and said brake, a switch arranged in said circuit so as to alternately connect said clutch and said brake with the source of current, a freely movable weighted lever having a curved slot, a pin engaging said slot and connecting said lever with said switch, a segment having projections adapted to act on said lever, the said switch being caused by said lever to either connect the said clutch or said brake with the source of current, while disconnecting the other.

3. In power looms with a freely falling lathe, the combination with a lathe actuating shaft of a driving mechanism including an electro-magnetic clutch, an electro-magnetic brake, a source of current, a common circuit for said clutch and said brake, a switch to connect the windings of the electro-magnets either of the clutch or the brake with the source of current while disconnecting the other, a movable rack-bar, a weighted lever forming a connecting link between said rack-bar and said switch, a pawl pivoted on the lathe and adapted to engage said rack-bar and a feeler connected with said pawl and adapted to enter the shuttle-box in case the shuttle fails to be properly boxed.

4. In power looms with a freely falling lathe, the combination with a lathe actuating mechanism of a driving mechanism including an electro-magnetic clutch, an electro-magnetic brake, a source of current, a common circuit for said clutch and brake, a switch A arranged in said circuit, a start and stop-motion bar, a freely movable weighted lever having a curved slot, a segment having projections adapted to act on said lever, a pin working in said slot and connecting said lever with said switch A, a current conductor, a switch C connecting either the said clutch or the said brake with the said current conductor while disconnecting the other, a projection on the lathe, a buffer in the path of movement of the lathe, a depending lever arranged in the path of said buffer and a weighted lever connecting said depending lever and said switch C for the purpose set forth.

In testimony whereof I have affixed my signature in presence of two witnesses.

JOSEF WINTERMAYR.
